G. W. SCOTT.
STORM FRONT FOR VEHICLES.
APPLICATION FILED APR. 24, 1912.
1,170,118.

Patented Feb. 1, 1916.

2 SHEETS—SHEET 2.

UNITED STATES PATENT OFFICE.

GEORGE W. SCOTT, OF TROY, OHIO.

STORM-FRONT FOR VEHICLES.

1,170,118.

Specification of Letters Patent. Patented Feb. 1, 1916.

Application filed April 24, 1912. Serial No. 692,813.

To all whom it may concern:

Be it known that I, GEORGE W. SCOTT, a citizen of the United States, residing at Troy, in the county of Miami and State of Ohio, have invented certain new and useful 5 Improvements in Storm-Fronts for Vehicles, of which the following is a specification.

My invention relates to improvements in storm fronts for vehicles, and more particularly to that type of storm fronts which are provided with side curtains mounted upon spring rollers.

The object of the invention is to provide 10 a front which is adapted to be attached to a vehicle body, whether such body is equipped with an extended dash or with a dash having its ends flush with the body.

A further object of the invention is to 15 provide simple and effective means for adjusting the side curtains so as to permit them to be swung in against the vehicle body when the front is attached to a body with an extended dash.

20 A further object of the invention is to improve upon the construction shown in my Letters Patent No. 1,142,061, dated June 8, 1915.

In the accompanying drawings: Figure 1 25 is a rear view of a storm front embodying my improvements shown attached to the body of a vehicle; the body being shown in section and one of the rolls and its curtain being broken away. Fig. 2 is a section on the line 2—2 of Fig. 1. Fig. 3 is a section on the line 3—3 of Fig. 1. Fig. 4 is a section taken on the same line as that of Fig. 2, but showing the parts in different 30 positions of adjustment. Fig. 5 is a perspective view of a part of one of the clamping devices. Fig. 6 is a perspective view of a portion of the removable cross bar.

Like parts are represented by similar 35 characters of reference throughout the several views.

In the said drawings, 1 represents the vehicle body, and 2 the dash thereof, the dash shown in the present case being of the extended type, meaning by that that the ends 40 thereof extend beyond the sides of the body. It should be explained here that some vehicles are equipped with these extended dashes and some with dashes having their ends flush with the sides of the body; also, 45 that these extensions vary in width and that the width of the vehicle bodies them-

selves also vary. It is necessary, therefore, in the building of a storm front to so construct it that it will be adapted to meet all these varying conditions, and when said 50 front is equipped with spring rollers it is quite essential that these rollers may be so adjusted as to lie close against the vehicle body under all conditions.

The storm front frame proper of the front 55 consists of side bars 3 and 4, a top bar 5, and an intermediate cross-bar 6; the space above this cross-bar being closed by transparent material in the usual way. The side arms 3 and 4 are also connected near their lower 60 ends by a bar 7, this bar 7 in the present case being made removable. The bar may be constructed of any suitable material, but it is preferably made of light channel iron, the ends of the bar being bent at right- 65 angles to form ears 7^a which are perforated to receive bolts 8 by which the bar is attached to the side portions 3 and 4. The storm front is secured to the dash of the vehicle body by clamping devices which may 70 be readily tightened to clamping position or loosened when it is desired to remove the front. Each of these clamping devices 75 consists of a part having a central slotted portion 9 and off-set hook-shaped portion 10, 80 together with a headed bolt 11 and a thumb-nut 12 on the screw-threaded portion of said bolt. Each end of the bar has a slotted opening 13 through which the bolt passes 85 and the off-set portions 10 of each clamping 90 device are so formed that they will extend above and below the bar.

In the normal position of the devices, such 95 as shown in Fig. 1, the bar 7 is on the inside of the dash and the off-set portions 10 project forwardly so that the hooks 14 thereof will engage the bead 2^a which is formed on all dashes; the hook 14 being rounded or formed on the arc of a circle to conform to the contour of the bead. By 100 tightening the thumbnut, these hooks will be caused to impinge tightly around these beads and thus clamp the frame of the front firmly to the dash. In some cases, for instance where the whip-socket is secured to 105 the end of the dash, it is very inconvenient, if not impossible, to apply the front in the manner shown in Fig. 1, because the whip-socket would interfere with the bar 7. In such case the bar 7 is detached, turned over 110 so that its bottom becomes its top and vice versa, reversed end to end to bring the ears

7^a in proper alignment with the angularly arranged side portions of the frame, and then again attached to the said frame. This throws the hooks 14 to the rear of the bar 5 instead of the front as shown in Fig. 4 so that the bar 7 may be placed on the front of the dash, and the hook 14 caused to engage the bead on the rear side of the dash, thus obviating any difficulty of attachment due 10 to the location of the whip-socket or from any other condition which may arise. By having the slotted openings 13 in the bar, the clamping devices may be adjusted laterally on the bar to accommodate dashes of 15 different widths. Each of the rollers 15 which carry the side curtains 16 has its upper trunnion 17 journaled loosely in an ear 18 projecting rearwardly from the frame of the front, the opening in the ear 18 being 20 somewhat larger than the trunnion 17 so as to permit the more or less free movement. The lower trunnion 19 is loosely and freely journaled in the bent end 20 of an arm 21 pivotally connected to the frame at a point 25 removed from the lower end thereof; the upper end of said arm having secured thereto a plate 22 adapted to be connected to a plate 23, fastened to the frame through the medium of a bolt 24, said plates having serrated faces which coöperate with each other to hold the arm in different positions of adjustment. The plate 23 is secured to the frame in such a position that the arm 21 will be located to the rear of the frame far 30 enough so that as the arm is adjusted in and out it will clear the thumb-nut. The intervening space between the arms and the curtains will be closed by a flap 25 of leather or other suitable material.

40 By this construction it will be seen that the storm front may be readily secured to any vehicle body of the type to which it is adapted and that when applied to a body which has an extended dash the curtain 45 may, by unloosening the nut on the bolt 24, be swung in against the vehicle body in the rear of the dash as shown in Fig. 1.

By having the cross-bar 7 removable, it 50 not only permits the same to be reversed in the manner before described, but it also permits the same to be attached to the side bars of the frame at any point so that the top cross bar 5 of the frame may be fitted in under the vehicle top and at the same time 55 have the clamping devices in proper position to properly clamp the dash. It will be further seen that each one of the clamping devices is entirely independent in its operation from the other clamping device; that 60 is, each clamping device clamps its end of the dash firmly to the cross-bar, the clamping strain being in a direction longitudinally of the vehicle body. By this construc-

tion, these clamping devices may form the sole support for the storm front and securely hold the same in position, the clamping action being such that there is no danger of slippage on the dash.

Having thus described my invention, I claim:—

1. In a storm front for vehicles, the combination, with a vehicle body and its dash, of a rigid frame together with means for securing same in position at the front of said body, a straight arm pivotally connected to the side of said frame near the lower end thereof and depending downwardly, the pivotal connection being such as to permit said arm to swing laterally relatively to said frame to a point within said frame, means at the pivotal point of said arm for holding said arm in different positions of adjustment relatively to said frame, and a vertically arranged curtain supported at its upper end by said frame and at its lower end by the lower end of said arm.

2. In a storm front for vehicles, the combination, with a vehicle body and its dash, of a rigid frame together with means for securing the same in position at the front of said body, a serrated portion on said frame near the lower end thereof, a straight arm having its upper end provided with serrations, means for adjustably securing the upper serrated end of said arm to said serrated frame portion such as to permit said arm to be swung laterally relatively to said frame, and a vertically arranged curtain supported at its upper end by said frame and at its lower end by the lower part of said arm.

3. In a storm front for vehicles, the combination, with a vehicle body having a dash provided with a bead at its outer edge, of a frame, a clamping device on each side of said frame, each of said clamping devices comprising a hook-shaped portion adapted to engage the bead of said dash and clamp the dash to said frame, said clamping devices being independent of each other.

4. In a storm front for vehicles, the combination, with a vehicle body having a dash, a frame, a removable cross-bar carried by said frame, a clamping device near each end of said cross-bar, each of said clamping devices having means for engaging and clamping the dash to said cross-bar, and means for adjusting said clamping devices on said cross-bar.

In testimony whereof, I have hereunto set my hand this 28th day of March 1912.

GEORGE W. SCOTT.
